UNITED STATES PATENT OFFICE.

JOHN KRASNODEMSKI, OF JOLIET, ILLINOIS.

TOY PISTOL.

1,310,754.

Specification of Letters Patent. Patented July 22, 1919.

Application filed January 2, 1919. Serial No. 269,202.

To all whom it may concern:

Be it known that I, JOHN KRASNODEMSKI, a citizen of Russia, residing at Joliet, in the county of Will and State of Illinois, have 5 invented certain new and useful Improvements in Toy Pistols, of which the following is a specification.

The primary object of the invention is the provision of a pistol adapted for shooting 10 marbles and similar missiles short distances, the same being in the nature of a toy and while the force of the projectile is insufficient to do any considerable damage, the same will travel through the air a short distance from 15 the operator.

A further object of the invention is to modify an ordinary form of pistol for shooting marbles without the employment of an explosive, the spring hammer of the pistol 20 being solely employed for this purpose.

A still further object of the invention is to provide a toy having the appearance of a pistol and operable similarly to the loading and shooting of an ordinary firearm, the device, however, dispensing with the use of an explosive and capable of projecting a marble or similar missile a short distance as found desirable.

In the drawings forming a part of this 30 application, like reference characters designate corresponding parts throughout the several views,

Figure 1 is an elevational view of the invention partially broken away illustrated in 35 its loaded and cocked position.

Fig. 2 is a top plan view of the invention.

Fig. 3 is a view similar to Fig. 2 partially broken away taken substantially upon line III—III of Fig. 1.

Fig. 4 is a transverse sectional view taken upon line IV—IV of Fig. 1.

Fig. 5 is a sectional view of a portion of the hammer taken upon line V—V of Fig. 6.

Fig. 6 is a transverse detail sectional view 45 of an end portion of the hammer taken upon an enlarged scale, and

Fig. 7 illustrates a game of marbles adapted to be played by means of my pistol.

My pistol provides a casting 10 having a 50 grip 11 angularly projecting from one end thereof and provided with the usual spring hammer 12 and trigger 13, a rear extension 14 of the hammer being serviceable in cocking the pistol. A barrel 15 is pivoted as at

55 16 to the casting 10 with its inner or rear end adapted for abutting the adjacent face

of the breech block 17 while a spring latch 18 upon the top of the barrel 15 normally maintains the barrel closed upon the breech as illustrated in the drawings.

60

A circular perforation 19 similar to a valve seat is provided through the breech block 17 and through this perforation, the filling point or nose 20 of the hammer 12 is adapted to project upon pulling the trigger 65 13. A resilient firing pad 21 formed of material such as rubber is secured to the nose 20 of the hammer so that upon pulling the trigger 13, the rubber pad 21 moves in the direction indicated by the arrow of Fig. 70 1 of the drawings violently striking a ball or marble 22 positioned within the barrel 15 upon the seat 19 after the manner of a ball valve.

Resilient means is also provided for normally maintaining the marble 22 in firing position although permitting the same to be projected outwardly through the barrel 15 when the hammer 12 is operated. This means consists of a curved arm 23 pivoted upon a point 24 in a chamber 25 of an extension 26 provided beneath the barrel 15 and by means of which extension, the barrel is hinged to the casting. A rod 27 is pivoted to the arm 23 while a spring 28 encircles the 85 rod 27 between the arm 23 and the adjacent lower side of the chamber 25. The arm 23 is normally held resiliently in the position illustrated in Fig. 1 permitting the marble 22 to be inserted in the open breech end of 90 the barrel 15 for resting on the seat 19 when the barrel is closed upon the breech 17 and locked by means of the latch 18.

The marble 22 projects about one-third thereof through the seat 19 and upon pulling the trigger 13 with the hammer 12 cocked, the pad 21 strikes the marble 22 forcibly driving the marble longitudinally through the barrel 15, the resilient arm 23 offering only a slight resistance to the movement of the marble and being automatically depressed, permitting the marble to pass the same. With the employment of an ordinary hammer spring, which it is not deemed necessary to herein illustrate, the force of 105 the hammer 12 driving the pad 21 against the marble 22 projects the marble some distance forwardly of the barrel 15, the said barrel serving to control the direction of flight of the missile.

95

110 The diameter of the bore 29 of the barrel 15 may be changed as found desirable, it

being only necessary that the arm 23 hold the marble 22 in its firing position without obstructing the passing of the marble through the barrel. The gun may be employed for shooting the marble 22 at other marbles such as 30 positioned within a ring 31 herein illustrated in Fig. 7 after the manner of the well known game of playing marbles by hand. When the pistol is "broken" 10 with the barrel 15 open by movement upon its pivot 16, the spring pressed arm 23 will resiliently hold the marble 22 between said arm and the upper side of the bore 29 at the breech end of the barrel so that the barrel 15 may be closed upon the breech block 17 to 15 position the marble 22 in its firing position upon the seat 19. The rubber pad 21 also assists in projecting the marble 22 by reason of its resiliency, the hammer 12 being cocked 20 in the usual manner and fired by pressing the trigger 13.

What I claim as new is:—

1. A toy pistol comprising a stock having a breech block with a perforation there- 25 through, a spring hammer pivoted in the stock with a firing end adapted to project through the perforation, a hinged barrel

adapted for closing upon the breech block and a spring pressed arm extending within the barrel adjacent the breech block adapted 30 for maintaining a missile seated in said perforation when the pistol is cocked.

2. A toy pistol having a casting and a stock, a spring pressed hammer and an operating trigger provided therefor, a barrel 35 hinged upon said casting, locking connections for the barrel when closed, a breech block carried by the casting against which the barrel is adapted to seat when closed and provided with a seating perforation for 40 a missile, a missile engaging pad upon the firing nose of the hammer adapted to forcibly project through said seat during the operation of the hammer, a pivoted arm normally projecting within the barrel, a positioning spring for said arm whereby a missile is lightly maintained upon its seat in the breech block in firing position within the path of movement of said pad.

In testimony whereof I affix my signature. 50

JOHN KRASNODEMSKI.
